By Charles S. Evans
HIS ATTORNEY.

UNITED STATES PATENT OFFICE

WENDELIN D. STARRETT, OF ALAMEDA, CALIFORNIA

CABLE CUTTER

Application filed April 4, 1928. Serial No. 267,347.

My invention relates to a cable cutting device, and the broad object of my invention is the provision of a cable cutter with means for cutting a cable smoothly.

5 Another object of my invention is the provision of a cable cutter of the character described with spaced cable supporting means; so that a cutting blade is adapted to cut the cable by moving in the supporting means 10 through the space provided.

Another object of my invention is the provision of a cable cutter of the character described, with a blade and supporting means adapted to encircle the cable while being cut.

15 A further object of my invention is the provision of a housing for a cutter of the character described, and having an opening in a side thereof for the insertion of the cable at any point between its ends.

20 My invention possesses other objects and valuable features, some of which will be set forth in the following description of my invention which is illustrated in the drawings forming part of the specification. It is to be understood that I do not limit myself to the showing made by the said description and drawings, as I may adopt varying forms of my invention within the scope of the claims.

25 Referring to the drawings:

30 Fig. 1 is a side vertical sectional view of the cable cutter of my invention. The plunger and cutting blade are shown in elevation to more clearly disclose the construction.

35 Fig. 2 is a front elevational view of the cutter, partly in section.

Fig. 3 is a horizontal sectional view taken in a plane indicated by the line 3—3 of Fig. 1.

40 Fig. 4 is a side elevational view of the blade and cable supporting means.

Fig. 5 is a front elevational view of the structure illustrated in Fig. 4.

Broadly my invention comprises a housing 45 open at both ends and a side; so that a cable can be inserted into the housing at any point between its ends. In the base of the housing are mounted two spaced cable supporting means, preferably dies, and a cutting blade is movably mounted in the housing and supporting means to pass through the space between

the supporting means, and thereby shear the cable upon being struck.

In terms of greater detail, the cable cutter of my invention comprises a housing 2 open at both ends and a side, thus providing a passage for the sidewise insertion of a cable. The base 3 of the housing has an elongated recess 4 for receiving the cable, and transversely of the recess are a pair of closely spaced grooves 6 and 7 for seating, in spaced relationship, the cable supporting and metal dies 8 and 9 respectively. The dies are notched in the edges so that a cable can be partially encircled thereby. Base 3 is also provided with an aperture 11 which is a continuation of the space between the dies; so that sheared strands of a cable being cut can pass therethrough.

Means are provided for movably mounting a cutting blade in the housing. An aperture is provided in the top 12 of the housing, for slideably holding plunger 13 having a head 14. The bottom of the plunger is recessed, and seated in the recess is a cutting blade 16 which is fixed to the plunger by means of a pin 17. Both ends of the pin project beyond the plunger and ride in grooves 18 and 19, thus holding the blade in alignment with the space between the dies 8 and 9. Preferably the blade is a thin flat sheet of metal provided with a substantially V shaped cutting edge, having a substantially V shaped notch therein; so that when the cable is being cut, the blade and dies cooperate to completely encircle the cable.

For reinforcing the housing, the closed side 45 thereof is provided with a strengthening rib 21, which also provides a convenient handle for the housing. On the rib is an aperture 22, upon which the device can be hung if so desired.

In cutting a cable, it is preferred to wrap the cable, at the point to be cut, with a wrapper 23, of the character described in my co-pending application, Serial No. 200,003, filed June 20, 1927. This prevents the spreading of strands and aids in obtaining a clean cut. After the cable is placed in position, the blade is struck heavy blows upon the head 14 of the plunger, thus shearing the cable when the blade passes between the supporting dies. It

is to be noted that since the blade passes between the supporting dies, a more efficient cutting is obtained, due to the fact that a shearing action takes place adjacent the edges of each die.

5 I claim:

1. A cable cutter comprising a housing, spaced dies having notched edges for supporting a cable in cutting position in the housing, and a blade having a notched edge and movably mounted in the housing to pass between the dies and cut the cable.
- 10 2. A cable cutter comprising a housing having a recessed base, spaced dies having notched edges and shaped to conform to said recess seated in said base for supporting a cable in cutting position, and a blade movably mounted in the housing to pass between the dies and cut the cable.
- 15 3. A cable cutter comprising a housing having a recessed base, spaced dies having notched edges and shaped to conform to said recess seated in said base for supporting a cable in cutting position, and a blade having a notched edge and movably mounted in the housing to pass between the dies and cut the cable.
- 20 4. A cable cutter comprising a housing, spaced dies for supporting a cable in cutting position in the housing, a plunger slidably mounted in the housing, and a blade fixed to the plunger to pass between the dies and cut the cable.
- 25 5. A cable cutter comprising a housing open at both ends and a side, spaced dies for supporting a cable in cutting position in the housing, and a blade movably mounted in the housing to pass between the dies and cut the cable.
- 30 6. A cable cutter comprising a housing having a base, spaced dies seated in the base for supporting a cable in cutting position, said base having an aperture which is a continuation of the space between the dies, and a blade movably mounted in the housing to pass between the dies and cut the cable.
- 35 7. A cable cutter comprising a housing open at both ends and a side for the sidewise insertion of a cable, spaced dies having notched edges for supporting a cable in cutting position in the housing, and a blade having a notched cutting edge and movably mounted in the housing to pass between the dies and cut the cable.
- 40 8. A cable cutter comprising a housing open at both ends and a side for the sidewise insertion of a cable, spaced dies having notched edges for supporting a cable in cutting position in the housing, and a blade having a notched substantially V-shaped cutting edge and movably mounted in the housing to pass between the dies and cut the cable.

In testimony whereof, I have hereunto set my hand.

65 WENDELIN D. STARRETT.
